(57) **CLAIM**

The ornamental design for a clamping tool as shown and described.

DESCRIPTION

FIG. 1 is a perspective view for a clamping tool showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof, showing the clamping tool in an open position.
The broken lines in the figures show portions of the clamping tool that form no part of the claimed design.
